UNITED STATES PATENT OFFICE.

IRA H. SPENCER, OF WEST HARTFORD, CONNECTICUT, ASSIGNOR TO THE SPENCER TURBINE CLEANER COMPANY, OF HARTFORD, CONNECTICUT, A CORPORATION OF CONNECTICUT.

CLEANING-TOOL.

1,162,412.

Specification of Letters Patent. Patented Nov. 30, 1915.

Application filed December 9, 1909. Serial No. 532,194.

To all whom it may concern:

Be it known that I, IRA H. SPENCER, a citizen of the United States, and a resident of West Hartford, in the county of Hartford and State of Connecticut, have invented a new and Improved Cleaning-Tool, of which the following is a specification.

My invention relates generally to the class of devices used for receiving and directing a current of air created by mechanical means, and more especially to that class used in cleaning operations; and the object of the invention is to provide a device of this class having novel features of advantage and utility.

A preferred form of construction of tool embodying the invention is illustrated in the accompanying drawings, in which—

Figure 1 is a top plan view of a tool embodying my invention. Fig. 2 is a view in side elevation of the same. Fig. 3 is a detail view on enlarged scale in central lengthwise section through the lower end of the handle and in cross-section through the tool showing the method of attachment of the tool to the handle. Fig. 4 is a view in cross-section through the handle on plane passing through the retaining ring. Fig. 5 is a detail view in lengthwise section through the upper end of the handle showing the means of attachment of a hose connection. Fig. 6 is a view in cross-section through the same on plane passing through the clamping ring.

The operation of cleaning by the popular method known at this time as "suction cleaning" is attended with more or less labor in the use of the tools, and it therefore becomes important that these tools and connections shall be so constructed as to lessen the labor required in their use. The weight of the tools is one of the greatest factors entering into this question of labor in operation, and it is therefore essential that the tool shall be of minimum weight and at the same time capable of resisting the rapid wear caused by the constant movement of the tool over carpets or like fabrics.

In the construction of a tool to embody these features an equally important requirement must be kept in mind, and that is, the reduction to a minimum of the friction

caused by currents moving through the tool, this in order to obtain a maximum degree 55 of vacuum at the mouth of the tool. This latter result is obtained in a tool having a smooth inner surface, and one formed of pressed sheet metal, as steel or the like, is found to possess this feature of smoothness 60 on its inner surface. When the whole tool, including the lips, extending about its mouth to provide a broad bearing surface and also to hold a buffer in place, are formed of this thin metal, however, it soon 65 becomes worn owing to the abrasive action of carpets and like surfaces caused by constant movement of the tool over them. Various means have been devised to enable the tool to resist this wear and thus prolong 70 its usefulness, these efforts being in the nature of a practically integral thickening of the mouth of the tool by bending the metal into various shapes and using reinforcements, but these have proved ineffectual owing to the expensive construction 75 but chiefly owing to the inability of such devices to withstand the wear.

I have found that a tool constructed as shown herein and embodying my invention 80 will fulfil the requirements hereinbefore mentioned.

In the illustration of such tool herein the numeral 7 denotes the handle of the tool preferably bent in curved form as shown in 85 Fig. 2 of the drawings and 8 the tool affixed to the lower end of the handle. These parts are constructed of metal as thin as possible in order to secure a minimum weight of tool, and the latter is preferably formed 90 from sheet metal pressed to shape, such a tool having the advantages above set out.

This tool has a lip 9 extending around its lower edge. A tool like this has heretofore been used, this lip affording the wearing 95 surface for the tool during operations but with the disadvantages hereinabove set out. In carrying out my invention I provide a removable mouth piece 10 having a tubular neck 11 projecting therefrom and of a size 100 and shape to snugly fit the inner surface of the tool 8. This fit will be such that while it will hold the shoe in place for all the requirements of use of the tool, yet it will not be so tight but that the mouth piece 105 may be removed when required for the pur-

pose of renewal or otherwise. A buffer or guard 12 is secured between the flange formed by the mouth piece 10 and the lip 9, this affording a means for removably securing the buffer in place.

- If a tool should be formed of sheet metal of a thickness requisite to provide the necessary wearing qualities for the shoe the tool would be unduly heavy. By my improved construction a tool having a body of minimum thickness may be pressed from sheet steel and a greater thickness may be provided for the wearing surface, this in the form of a removable mouth piece. The weight of this sheet metal tool fitted with a mouth piece having a wearing face of increased thickness is but a trifle more than it would be without the mouth piece, but it is not essential to the invention even that the mouth piece shall be of increased thickness, as they are comparatively inexpensive and may be replaced at a minimum cost, or several may be supplied with the tool as originally furnished.
- It is desirable that the tools may be readily removed from the handle to allow interchange of the tools.

In such a tool heretofore invented by me and in which the tool is swivelly mounted on a part located at an angle to the main part of the handle, the elbow constituting this angle has been a part of the tool, the elbow being removably secured to the handle. This necessitated the formation of two joints, that embodying the swivel and that embodying the removable attachment to the handle, and this construction necessitated the formation of an elbow for each tool.

In order to lessen the initial cost of the tool, I have embodied in the tool herein shown and described a construction in which the elbow is formed as an integral part of the handle, necessitating but a single elbow for all of the tools in connection with which the handle is used, and it also omits one of the joints in the entire structure. The connection serves a double purpose, embodying the swiveled mount for the tool heretofore used and also the removable connection with the handle.

The tool thus having but slight projection is extremely compact, requiring comparatively small space for storage or packing for transportation. In carrying out this idea a nipple 13 is rigidly secured to the back of the tool 8 and a groove 14 is formed in the outer surface of this nipple. The nipple has an opening for the passage of air and is of a size to fit the tubular end 15 of the handle, which tubular end as shown in Fig. 3 is preferably slightly enlarged to form a shoulder 16 providing a stop to determine the position of the nipple within the end of the handle. A retaining ring 17 is formed to fit the recess 14, this retaining ring being

split and of such length that when its ends meet, as shown in Fig. 4, it will be loose enough within the recess 14 to allow free turning movement of the nipple 13 within the ring. A clamp sleeve 18 is mounted upon a screw-threaded outer surface of the lower end of the handle, in the construction herein shown a collar 19 secured to the handle having this threaded surface. This sleeve has an inner beveled clamping surface 20 arranged to engage the ring 17 to close its ends. This sleeve is but slightly larger than the end of the handle upon which it is supported and the tool is thus free from projections not conforming to the general shape of the handle. A stop ring 21, in the form of a split ring, is snapped into a groove 22 at the rear end of the sleeve 18, this ring contacting with the collar 19 and serving as a stop to limit the movement in one direction of the sleeve. The retaining ring 17 is of such size that it will pass into the space between the inner surface of the sleeve 18 and the outer surface of the nipple 13, and in practice this ring is made a trifle smaller in diameter than the width of this space. In any event, the ring will be of such size that it may be passed into the sleeve 18 and located in the groove 14, and when located in such groove will be retained therein by the action of the beveled portion 20 of the sleeve.

A similar construction is provided at the opposite end of the handle for the attachment of a hose connection 23, this connection having a threaded surface 24 for engagement of the clamping sleeve 18 which may be a duplicate of that hereinbefore described and having the stop ring 22 acting in the same manner. The beveled inner surface 20 of the collar in this instance acts upon a clamp ring 25 which is split but the inner ends of which do not meet in the action of the parts. A clamp ring round in cross-section may be employed if desired, or a fibrous ring may be used, but the preferred form of ring and as shown herein, is one of a shape in cross-section to conform to the space between the sleeve and the outer surface of the handle 7. As the clamping sleeve 18 is moved along the handle in a direction to clamp the ring the latter is tightly bound against the handle, holding the parts firmly in position.

It is desirable that the joint where the hose is attached to the handle shall be air-tight, and to this end the ring 25 is formed as shown in dotted outline in Fig. 5, the packing ends 26lapping past each other to provide an air-tight packing, spaces 27 being provided to allow for contraction of the ring.

It will be understood that my invention is not limited to the preferred form of construction of parts and their details as mentioned by the claims herein, but that such

construction may be departed from to a greater or lesser extent without avoiding the invention.

I claim—

- 5 1. A tool having a mouth for the admission of air, and a flange extending thereabout, a mouth piece including a tubular projection removably held within said mouth and a wearing flange, and a buffer held between said flanges.
- 10

2. A tool having a mouth for the admission of air, a mouth piece including a tubular projection removably held within said mouth, and a buffer clamped between said mouth piece and the edge of the mouth 15 opening into the tool.

IRA H. SPENCER.
